DESIGN FOR A KNOCKDOWN DOLL'S TABLE

Jean F. de Hymel, Pasadena, Calif.

Application April 21, 1941, Serial No. 100,531

Term of patent 3½ years

To all whom it may concern:

Be it known that I, Jean F. de Hymel, a citizen of the United States and a resident of Pasadena, in the county of Los Angeles and State of California, have invented a new, original, and ornamental Design for a Knockdown Doll's Table, of which the following is a specification, reference being had to the accompanying drawing, forming a part thereof.

Referring to the drawing:

I claim:

The ornamental design for a knockdown doll's table, substantially as shown.

JEAN F. DE HYMEL.
